ALFRED C. STEWART, OF LOS ANGELES, CALIFORNIA.

ART OF REFRIGERATION.

Application filed October 30, 1920. Serial No. 420,583.

To all whom it may concern:

Be it known that I, ALFRED C. STEWART, a citizen of the United States, residing at Los Angeles, in the county of Los Angeles 5 and State of California, have invented a new and useful Improvement in the Art of Refrigeration, of which the following is a specification.

This invention relates to means for refrigeration of air, or other fluid medium, and the main object of the invention is to provide a simple and effective method and means for this purpose in which the refrigerating action is obtained by forced expansion of a liquid, as hereinafter set forth.

The accompanying drawing illustrates an apparatus suitable for carrying out my invention, and referring thereto:

Fig. 1 is a vertical section of such an apparatus;

Fig. 2 is a section on line 2—2 in Fig. 1.

The apparatus shown in the drawing comprises a casing 1, preferably circular in shape, and provided with inlet and outlet means 2 and 3 for conducting therethrough the air, or other medium, which is to be refrigerated; and a rotating device mounted within said casing and provided with passage means for conducting the liquid there-through and for restraining the movement of said liquid, as hereinafter described, to effect a forced expansion thereof under centrifugal action due to the rotation of said device. Said rotary device may be mounted on a vertical shaft 5 supported in upper and lower bearings 6 and 7, said shaft being provided with an operating means, such as pulley 8, whereby it may be rotated at high speed. A passage 9 is provided in said shaft 40 communicating with an inlet 10 for water, or other liquid, and also communicating with passages 11 in a cross-head 12 on said shaft. Tubes 13 are mounted in said cross-head so as to extend diametrically with 45 respect to said shaft, the internal passage 15 of each tube communicating through one of the aforesaid passages 11 with the passage 9 in the said shaft, and a plug or diaphragm 14 is interposed between the internal 50 passage 15 of each tube 13 and the corresponding passage 11, said plug or diaphragm 14 being of porous or pervious material, such as leather, porous earthenware, etc., so as to permit of the flow of liquid from passages 11 to passage 15 through capillary openings which ensure uniform slow move-

ment and restrain or retard the movement of the liquid, as hereinafter described.

A similar plug or diaphragm 16 is provided at the outer end of each tube 13, restraining the movement of the liquid, or fluid medium, from the tubes. A discharge nozzle 17 may be provided at the outer end of each tube 13 for conducting the discharged liquid to an outlet trough 18 communicating with an outlet passage 19. Passages 15 constitute expansion chambers wherein the liquid is evaporated as herein-after explained. Partition means 21 and 22 may be provided on the stationary and 70 rotary parts 1 and 13, respectively, to retain the air to be cooled in contact with parts 13. Casing 1 may be provided with heat insulating means 23.

The operation is as follows:

Water, or other liquid, is allowed to flow from the inlet 10 through passages 9, 11 and 15 in the shaft 5, and parts 12 and 13, and the rotary member is then set in rapid rotation by driving means 8, so as to cause 80 centrifugal action to be exerted on the liquid in the expansion chamber 15 with the result that such liquid tends to move outwardly through the porous plugs 15 and 16. The centrifugal effect at the outer plugs is, 85 however, greater than at the inner plug, with the result that the liquid tends to move out of the expansion chamber through plug 16 faster than it runs in through plug 14, and the body of liquid is thereby disrupted 90 and separated into two columns, one within the passages 9 and 11, and the other within nozzle 17 and extending inwardly through plug 16 and into expansion chamber 15. When the centrifugal action on the last 95 named body of liquid just balances the difference between atmospheric pressure and whatever vapor tension may exist in the expansion chamber 15, equilibrium will be attained, and for any given speed of the rotary member within certain limits there is a certain length of the column of liquid constituted by the last named body of liquid within and adjacent to the outer porous plug 16, which by its centrifugal action will 100 present the requisite balance. Under these conditions the liquid will flow gradually through the inner porous plug 14 and will be continuously evaporated at the inner surface thereof, and then recondensed as it 110 reaches the outer column of liquid adjacent the outer plug 16, such recondensation being

due to the increase of pressure resulting from the centrifugal action on the body of vapor in the expansion chamber 15. By making the plugs 14 and 16 sufficiently close 5 grained or restraining in action the amount of liquid supplied at the outer surface of the inner plug may be sufficiently small to enable substantially complete evaporation of the liquid as it reaches such surfaces; any 10 excess of liquid supplied in this manner will flow outwardly through expansion chamber 15 and pass out through the nozzle 17 along with the liquid condensed as aforesaid. The continuous evaporation of the liquid in the 15 expansion chamber 15 causes absorption of heat due to the latent heat of the liquid, thereby cooling the tubes 13 and eventually cooling the body of gas, or other medium, which is passed through the casing 1 by 20 inlet and outlet means 2 and 3. Such cooling action will be restricted to the inner portions of tubes 13 adjacent to the evaporating surfaces aforesaid. In order to conserve the resulting cooling action the partition means 25 21 and 22 and heat insulating means 23 may be provided, as aforesaid.

What I claim is:

1. The process of refrigeration which 30 consists in revolving an expansion chamber which extends radially with respect to the center of revolution, admitting an expandable medium through a porous body to the inner end of said expansion chamber, and withdrawing such medium from said 35 chamber through a porous body at the outer end of said chamber, the medium being subjected to expansion and consequent cooling by reason of the greater centrifugal force at the outer end of said chamber as compared 40 with that at the inner end thereof.

2. A refrigerating apparatus comprising 45 a rotary member provided with a radially

extending expansion chamber having porous plugs at its inner and outer end, inlet means for supplying liquid to the chamber through 45 said inner porous plug, and outlet means for discharging liquid from the outer porous plug, the construction being such that the liquid is forced through the plugs by centrifugal action, which is greater at the outer 50 plug than at the inner plug, so as to effect expansion of the liquid in the expansion chamber.

3. A refrigerating apparatus comprising 55 a rotary member provided with a radially extending expansion chamber having inlet means for supplying liquid to the inner portion of said expansion chamber, a porous member at said inlet means for restraining said supply, said expansion chamber being 60 provided with an outlet at its outer end and a porous body at said outlet through which the effluent from the chamber passes, and means for rotating said rotary member at a high speed to produce centrifugal action on 65 the liquid therein so as to cause evaporation of such liquid as it passes through said restraining means into said expansion chamber.

4. A refrigerating apparatus comprising 70 a shaft, provided with means for rotation thereof, a tubular member extending radially from said shaft, said tubular member being provided at its inner end with means for supplying liquid thereto and at its outer 75 end with means for discharging liquid, and restraining means consisting of porous plugs at the inner and outer ends of said tubular member for controlling the movement of liquid therethrough.

In testimony whereof I have hereunto subscribed my name this 14th day of October, 1920.

ALFRED C. STEWART.
